United States Patent [19]

Marks

[11] Patent Number: Des. 335,464

[45] Date of Patent: ** May 11, 1993

[54] ANALYTICAL INSTRUMENT FOR TESTING
PARAMETERS OF POOL WATER

[75] Inventor: Colin E. Marks, Tyne & Wear,
England

[73] Assignee: Palintest Ltd., Tyne & Wear,
England

[**] Term: 14 Years

[21] Appl. No.: 528,740

[22] Filed: May 24, 1990

[30] Foreign Application Priority Data

Nov. 28, 1989 [GB] United Kingdom 2002952

[57] CLAIM

The ornamental design for an analytical instrument for testing parameters of pool water, as shown and described.

DESCRIPTION

FIG. 1 is a front perspective view of an analytical instrument for testing parameters of pool water, showing our new design;

FIG. 2 is a rear perspective view thereof;

FIG. 3 is a front perspective view thereof, with the top in open position; and,

FIG. 4 is a rear perspective view thereof.

The bottom plan view of the analytical instrument for testing parameters of pool water, which is not disclosed is plain and unornamented.

FIG. 1

FIG. 2

FIG. 3**FIG. 4**
